UNITED STATES PATENT OFFICE

JOSEPH H. SIEMER, OF ST. LOUIS, MISSOURI

PERFORATING PUNCH

Application filed May 8, 1929. Serial No. 361,475.

My invention is an improvement in devices for punching holes, and is in the form of an implement for punching holes in material by which the cutting die may be accurately centered and the cut-out piece ejected from the die.

The primary object of my invention is to provide an accurate perforating punch especially adapted for use by pattern makers in the shoe manufacturing trade for facilitating the operation of forming the usual perforations in the patterns, in the present instance providing for quickly and accurately centering the punch on the dots or other guiding marks with provision for ejecting the cut-out portion of the material.

A further object of my invention is to provide a punching tool or implement of this character which is strong and durable in construction, simple and effective in operation, and in which the parts constituting the same can be readily separated for renewal or repair.

With these principal objects in view my invention consists of a manually operated punch for forming perforations in material of different kinds comprising a handle portion in the form of a bar one end of which is shaped to receive the blows of a hammer used in operating the punch while the other end is bored and threaded, a tubular die threaded in the outer end of the bore, a plunger working through the die to eject the cut-out material, and a spring within the bore for actuating the plunger, the working end of the plunger being provided with a teat serving to center the punch for accuracy in properly lining the perforations; all as hereinafter fully described and more specifically set forth in the appended claims.

In the drawings:—

Figure 1 is a side elevation of a perforating punch constructed in accordance with my invention.

Fig. 2 is a similar view with a part of the body portion or handle broken away.

Fig. 3 is a longitudinal sectional view through the punching tool or implement, and

Figs. 4 and 5 are detail views of the head of the punch and cutting die, respectively.

In carrying out my invention the body portion forming the handle 10 of the implement is a steel bar preferably cylindrical in cross section with the end thereof against which the hammer strikes slightly beveled, as is usual in tools of this general character, while into the other end of said handle extends a bore 11 threaded for a short distance 55 from its outer end, as indicated at 12. Threaded into the outer end of the bore is a tubular cutting die 13, with an integral collar 14 at the lower end of its threaded portion 13a corresponding in diameter with that 60 of the bar or handle and an internal shoulder 15 at the upper end of the central bore 16 through said die. The lower end of the tubular die is provided with a beveled cutting edge 17 which is circular in shape to form 65 a round hole in the material, and for the purpose of ejecting the cut-out material from the cutting die a plunger 18 is mounted in the aforesaid bore 16 with a head 19 at its upper end adapted to engage the shoulder 15 for 70 limiting the outward movement of the plunger or ejector, it being noted that the length of the latter is such that it projects slightly when the head is in engagement with the shoulder. The plunger is operated to eject 75 the cut-out material by means of a helical spring 20 contained within the bore in the handle and interposed between the inner end of said bore and the head of the plunger, and in order to accurately center the die the plunger or ejector is provided centrally with 80 a projecting teat 21 sharpened to a point. 85

By reference to the drawings it will be seen that the tubular cutting die is threaded into the end of the handle so as to be rigidly connected thereto, and that said die is reduced in diameter for a greater portion of its length from the cutting edge whereby it can be easily manipulated to locate the teat on the dot or point at which the hole is to be made.

In the operation of the punch in perforating patterns the die is properly centered by means of the teat which is located to puncture the dot on the pattern and then by strik- 95 100

ing the upper end of the handle or bar with a hammer the die will cut through the material and the cut-out piece of material being forced into the tubular die will be ejected by the spring-actuated plunger as the implement is removed. This operation is repeated with respect to the other dots on the pattern to form the necessary perforations therein, and it will be obvious that the implement 10 can be manipulated quickly to facilitate the operation of perforating patterns. Furthermore by the particular construction and assemblage of the parts I provide a strong and durable implement which is of special utility 15 to pattern makers in the shoe manufacturing trade, although of course it can be used by others for punching holes, and consequently the diameter of the circular cutting edge may be increased or diminished according to the 20 size of hole to be punched.

I claim:

A perforating punch for pattern makers comprising a bar forming the handle of the punch and having a longitudinal bore extending inwardly from the outer end thereof, a tubular die threaded in the outer end of said bore and having an integral collar bearing against the end of the handle, the tubular die having an opening therethrough and the 25 outer end portion thereof being reduced in diameter and tapered from the said collar, an annular shoulder at the inner end of the opening through the tubular die formed by enlarging said opening, a plunger working 30 in the tubular die to eject the material cut out thereby and having a head at its upper end working in the enlarged portion of the opening and adapted to engage the aforesaid shoulder, a seat formed integrally with and 35 projecting from the outer end of the plunger at the center thereof to form a point for centering the punch, and a spring confined 40 within the bore to bear against the head of the plunger for projecting the same.

JOSEPH H. SIEMER.
